UNITED STATES PATENT OFFICE.

ARTHUR C. KLECKNER, OF RACINE, WISCONSIN, ASSIGNOR TO WEBSTER ELECTRIC COMPANY, OF RACINE, WISCONSIN, A CORPORATION OF WISCONSIN.

ACTUATING MEANS FOR MAGNETOS.

Application filed July 2, 1924. Serial No. 723,801.

My invention relates to actuating means for magnetos of the oscillating armature type, the chief purpose of the invention being to insure a full spark current at all engine speeds by generating the spark current on the initial movement of the armature rather than on its recoil movement. Further objects of my invention are the use of a tripping mechanism having a cocking feature combined therewith to produce a quick current generating impulse; the provision of an improved form of tripping finger, and the provision of improved means for locking the armature until it is released for its current generating movement.

In the usual form of oscillating magneto, the armature is brought to a cocked position against spring pressure, and the armature then is allowed to snap back to its normal position, the spark current being generated on this quick recoil movement. It has been found, however, that at high engine speeds, the cocking or initial movement of the armature is so fast and is followed so soon by the quick recoil movement, that insufficient opportunity is allowed for the current necessarily generated by this cocking movement to die out before the newly created spark current on the recoil surges through the coils in the opposite direction. As a result, the spark current has to build up—not from a zero value—but from a value on the other side of the zero line, corresponding to a current flow in the opposite direction. For this reason, the spark current cannot build up to as great a peak value during high engine speeds as at slow or moderate speeds.

I depart from this practice by using this initial oscillation of the armature, corresponding to the cocking movement in prior practice, for generating the spark current, and use the recoil merely for returning the armature to its normal position. This normal position is the state of rest that the armature assumes between firing strokes of the engine, and is of considerably longer duration than the actuating period of the magneto. Thus, this entire time interval between the recoil movement of the armature for one engine cycle and the initial movement of the armature for the succeeding engine cycle is allowed for any currents to die out before the spark current is generated.

The foregoing and other objects are set forth more in detail in the following de-

scription of a magneto embodying a preferable adaptation of the invention, and are disclosed in the drawings, wherein

Figure 1 is a side elevation of a single cylinder internal combustion engine provided with the magneto of my invention;

Figure 2 is a plan view of the magneto;

Figures 3, 4, and 5 are vertical transverse sections taken respectively on the lines 3—3, 4—4, and 5—5 of Figure 2;

Figure 6 is a view similar to Figure 3, but showing the parts in the position they assume at the completion of the tripping stroke; and

Figure 7 is a view similar to Figure 3, but showing a modified form of tripping finger.

The engine 10 shown in Figure 1 is provided with the usual reciprocating valve rod 11, the magneto 12 being secured to the engine casting by means of a bracket 13 on the magneto and so arranged that the stationary and movable electrodes 14 and 15 extend through a suitable aperture in the engine wall to the combustion chamber. A plurality of U-shaped magnets 16 are superimposed and fitted together to form a unit, the legs of which are provided with opposed E-shaped pole pieces 17, the middle bars 18 of the E-shaped pole pieces carrying the coils 19, in which the sparking current is generated. The end terminals of this pair of coils are connected with the electrodes 14 and 15. Between the pole pieces 17 is rotatably mounted an armature 21 having a substantially X-shaped cross section.

In the normal position shown in Figure 5, the magnetic path between the pole pieces leads through the middle bars 18 and across the opposed arms 22 of the armature. When the armature is given a short but quick clockwise rotation, the lines of force along this path are stretched and finally abruptly broken as the arms 22 of the armature move out of proximity to the middle bars 18, and the other arms 23 of the armature, as well as the arms 22, close paths through the upper and lower bars of the E-shaped pole pieces. As pointed out in the introduction to the specification, this current generating movement of the armature is made on the cocking or initial movement of the armature rather than on the recoil movement. The means for effecting this sudden forward movement of the armature oscillation will now be described.

The armature shaft 22' is extended beyond its bearings at one end of the magneto and is there provided with a cam disc 27, the function of which I shall presently describe. A recoil spring 24 is coiled about this shaft 22' having one end secured by pin 25 to the cam disc 27 and the other end secured by pin 26 to the magneto frame. The tension of this spring normally tends to return the armature to its normal position indicated in Figure 5 and there yieldingly hold it. The armature shaft 22' is also provided with a push finger 28, which I shall presently describe. As shown in Figure 4, the cam disc 27 is provided with diametrically opposed depressions 29, into which fit rollers 30 carried on the end of opposed plungers 31 slidably journaled in bearings 32 extending rearwardly from the magneto frame. Compression springs 33 are inserted between the outer bearings 32 and washers secured to the plungers 31 for urging the rollers 30 radially against the periphery of the cam disc 27. The forward or clockwise ends 25 of the depressions 29 are extended outwardly as at 34 to stop the armature against counter-clockwise rotation past the normal position to which it is returned by the coiled spring 24. While the depressions 29 tend to hold the disc 27 against clockwise rotation, a predetermined torsional strain on the armature shaft will cause the rollers to ride out of the depressions 29 against the yielding pressure of the springs 33. I shall next 30 describe the means I employ for unlocking and rotating the armature.

Disposed in horizontal alignment with the push finger 28 is a trip finger 35 pivoted at 36 to a valve rod clamp 37 which is rigidly secured to the valve rod 11, as shown in Figure 1. An eccentric sleeve 36' may be interposed between the pivot 36 and the trip finger 35. By the operation of a suitable handle, not shown, this eccentric sleeve 40 may be rotated to advance or retard the spark. The trip finger 35 is provided with aligned longitudinally disposed bearings 38, within which is reciprocally journaled a push rod 39, which is normally urged away from the pivot 36 by a compression spring 40 which holds the shoulder 41 of the push rod against one of the bearings 38 to limit relative movement of the push rod and trip finger. The trip finger is provided with an extension 42 which normally extends along the bottom of, and to within a short distance from the end of, the push rod 39.

The push finger 28 is provided with an arm 43 into which is threaded a downwardly extending cap screw 44. A strong looped spring 45 disposed about the pivot 36 tends to spring the trip finger 35 upwardly so that the cap screw 44 contacts the upper surface of the push rod 39. As shown in Figure 3, the forward edge of the push

rod 39 engages the end of the push finger 28. As the valve rod 11 in its reciprocation is moved to the left, the clamp 37 will cause a similar movement of the trip finger 35, pressing the end of the push rod 39 against the push finger 28. Because the armature is locked against rotation by the rollers 30, the push rod will yield against the pressure of the spring 40 until the forward extension 42 of the trip finger contacts the push finger 28. Since this establishes a positive connection between the valve rod and the push finger, there is sufficient rotary force imparted to the armature shaft 22' to cause the rollers 30 to ride out of the depressions 29 against the yielding force of the springs 33, freeing the armature from all mechanical resistance to turning other than the incidental friction of the armature bearings and the rollers 30.

It will be noted, however, that by the time the extension 42 contacts the push finger 28, the push rod 39 will have assumed a cocked position because of the compression of the spring 40. As soon as the cam disc 27 is unlocked, the cocked push rod 39 will shoot forwardly considerably faster than the timed travel of the trip finger, imparting a quick rotation to the armature. The arc through which the armature is thus rotated may be determined by adjustment of the cap screw 44, which, as the push finger 28 rotates, pushes the push rod 39 downwardly and out of engagement with the push finger.

At the proper time an arm 46 on the push finger 28 contacts the electrode arm 47, rotating the electrode shaft 48, the opposite end of which carries the movable electrode 15, pulling the latter away from the stationary electrode 14 for the purpose of drawing out a spark, as is usual in low tension magneto equipment.

As soon as the push rod 39 is swung out of engagement with the push finger, the spring 24 snaps the armature back to its original position where the rollers 30 again lock the armature shaft against rotation. It will thus be seen that the recoil movement of the spring 24 is not utilized for any current generating purposes, but merely to return the parts to their normal position in readiness for the next oscillation. The entire time interval between the recoil action of the spring 24 and the tripping of the push finger 28 in the succeeding engine cycle is allowed, during which time, of course, all current generated in the coils will have died out. When the armature is again tripped, the spark current will build up from a zero value, and not from a value on the other side of the zero line.

In Figure 7 I have shown a modified form of trip finger, in which the positively moved trip finger 35' does not itself contact the push finger 28, but positively engages the

push rod 39' after the latter has cocked the yielding spring 40'. In its detailed construction, the push finger 35' is hollowed by a bore within which reciprocates the rear 5 end of the push rod 39', a positive stop for the shoulder 41' on the push rod being afforded by a cap 49 threaded over the open end of the push finger 35'. The spring 40' is cocked while the shoulder 41' travels from 10 the end of the cap 49 to the open end of the push finger 35' which then positively pushes the push rod 39' forwardly to trip the armature.

Having thus described my invention, what 15 I claim is:

1. The combination with a magneto having an armature rotatably mounted therein and a winding therefor, forward and also backward rotation of which armature generates a current in said winding, of a pair of electrodes, a push finger on said armature, a trip finger, means for moving said trip finger, a spring pressed latch for locking said armature in a normal position, a push finger 20 engaging element movably mounted on said trip finger, a spring disposed between said element and said trip finger adapted to be cocked by movement of said trip finger, said trip finger after said spring is cocked 25 moving said push finger to unlock said armature and permit said spring to snap said element for rotating said armature forwardly, means for returning said armature to its normal position, and means for utilizing the 30 current generated in said winding on said forward rotation to produce a spark between said electrodes.

2. The combination with a magneto having a winding and a rotatably mounted 40 armature, of means for oscillating said armature comprising a driving element having a timed movement, an impulse mechanism interposed between said element and said armature for rotating the latter forwardly, 45 means for rotating said armature backwardly to a normal position, and a spring pressed latch for releasably locking said armature in normal position.

3. Means for actuating the armature of an 50 oscillating armature magneto comprising a spring for bringing said armature to a nor-

mal position, a cam disc having depressions therein and secured to said armature, spring pressed means engaging said depressions when said armature is in normal position, a 55 timed driving element, and an impulse mechanism between said element and said armature for rotating said armature forwardly against the force of said spring.

4. The combination with a magneto having a rotatably mounted oscillating armature, of a driving element having a timed movement, a push arm on said armature, a trip finger mounted on said element, a push rod slidably supported on said finger for engaging said push arm, a spring between said rod and said finger, a cam disc having locking shoulders thereon, a spring pressed roller engaging between said shoulders for holding said armature against rotation to 70 cock said spring, means on said finger for unlocking said locking means, and a spring to return said armature to a normal position.

5. In an oscillatory magneto, the combination of a rotary armature having a normal 75 position between firing strokes of the engine, a grooved cam disc fixed to rotate with said armature and a resilient roller engaging in the groove of said disc to lock said armature in normal position, a pair of circuit controlling members, mechanism for imparting a current generating impulse to said armature in its initial oscillation away from said normal position, and means for separating said circuit controlling members during said initial oscillation.

6. In an oscillatory magneto, the combination of a rotary armature having a normal position, resilient means to lock said armature in normal position, camming means to 90 cam said resilient means out of locking position, a pair of circuit controlling members, means for oscillating said armature away from said normal position, means for oscillating said armature back to said normal 95 position, and means for separating said circuit controlling members during the oscillation of said armature away from said normal position.

In witness whereof, I hereunto subscribe 100 my name this 17th day of May, 1924.

ARTHUR C. KLECKNER.
